UNITED STATES PATENT OFFICE

NELSON H. HENDERSON, OF SYRACUSE, NEW YORK

MIXING FAUCET

Application filed August 13, 1928. Serial No. 299,235.

The title mixing faucet as used herein is intended to indicate only such faucets as have one operating lever for both hot and cold water valves and not the double swing spout faucets with a hot water valve and also a cold water valve separately controlled.

This faucet has new characteristics and combines several desirable features as follows:

10 One operating lever only is necessary for both hot and cold water; this lever will stay wide open when released, if desired. A swinging type of discharge nozzle can be used and by swinging the operating lever from side to side the discharge can be made hot or cold or any desired mixture thereof.

In addition to the above the faucet has an extra outlet for connection to a flexible hose or spray useful in cleaning dishes, vegetables, 20 etc.

There is also a novel self grinding feature in connection with the valve seat.

The extra outlet is arranged so that it may be connected to a container for soap or washing compound so the water passing to the flexible hose is more efficient for washing purposes. When the water is passing to this extra outlet it is closed off from going to the regular swinging discharge nozzle.

30 This invention consists in the novel manner of arranging the different parts of the faucet to accomplish all the above features and at the same time produce an article of pleasing appearance and practical to build.

35 It further consists of other novel features of construction and advantage, each of which will be hereafter fully set forth.

For the purpose of illustrating my invention I have shown an embodiment of this in the accompanying drawings.

I wish it understood that the various novel features of which my invention consists can be organized in other forms and that my invention is not limited to the precise arrange-

ment as herein described and shown or to use in the household only.

Reference is now made to the accompanying drawings in which Fig. 1 is a front view of the faucet.

Fig. 2 is a top view indicating different positions of swinging nozzle and operating lever by dotted lines.

Fig. 3 is a sectional view taken on line X—X of Fig. 5.

Fig. 4 is a sectional view taken on line M—M of Fig. 5 showing the valve closed.

Fig. 5 is a partial sectional and plan view taken on line Y—Y of Fig. 4, and turned through ninety degrees.

Fig. 6 is a sectional view on line M—M showing the valve open with the spout turned to divert water to the spray.

In describing these views it will be seen that there are two sources of water supply and that in Figures 3 and 4 one of these is entirely closed while in Fig. 6 both will be partly open.

In Fig. 2 are indicated by dotted lines different positions of the discharge nozzle marked P and R, also different positions of the valve operating lever marked S and T.

Fig. 3 shows the relation of the valve parts which would cut off one source of water supply entirely and in which the operating lever would take the position indicated at S in case the valve was opened.

In Fig. 6 the operating lever has a position midway between those indicated at S and T.

In the drawings similar reference characters are employed to designate the same parts throughout.

(1) represents the main valve body, (2) is the valve stem which carries a valve disc (3). At (4) and (5) are shown the inlets for hot and cold water respectively. (6) is the operating lever. (7) is a rotary valve or disc higher on one side than the other. It operates to shut off completely or partly the hot

or cold water inlets when it is twisted by the square extension of the valve stem which slides up and down in the square hole at the center. (8) is the swinging discharge nozzle of the faucet which will deliver water while swinging through an arc of about 180 degrees but if pushed farther against the wall of the sink as indicated by dotted lines at P and R, Fig. 2, the water will be cut off and a passage will be opened from the interior of the

10 valve to the stationary outlet (14).

(9) is the passage or opening on the inside of the discharge nozzle which communicates with opening (10) in the main valve body. 15 It will be seen that when the swinging nozzle (8) is turned more than 90 degrees either way from the center position shown in Fig. 5 that the openings (9) and (10) cease to register with each other and the water will 20 stop flowing from the nozzle. If the nozzle is now turned still further as shown in Fig. 6 and indicated at P and R Fig. 2 one of the openings (11) will register with openings (12) and (13) in the valve body and the 25 water will be discharged through outlet (14). The spring (15) holds the valve (8) against the valve seat against the water pressure under the seat and as there will be some twisting of the valve by its operator before being 30 opened this will keep the valve tight by continually grinding it to the seat.

It is to be understood that this faucet can be used for other liquids other than water as well as gases in connection with soda fountains and the like.

Therefore I wish it understood that obvious changes and substitutions may be made without evading the scope of the appended claims.

40 What I claim is:

1. In a mixing faucet, a swinging discharge nozzle, a receiving chamber surrounded by a cylindrical wall, having two openings, the discharge nozzle being arranged to swing about a vertical axis and having passages which are adapted to operate to register with the openings in the cylindrical wall.

45 2. In a mixing faucet, a valve body surrounding a mixing chamber, a receiving chamber with a cylindrical wall, a swinging discharge nozzle arranged to turn on the outside of the cylindrical wall, a passage in the body of the discharge nozzle, an outlet in the wall of the receiving chamber in line with the passage in the valve body, the discharge nozzle operating to swing into a position where its passage will register with the opening in the receiving chamber wall 55 and also with the passage in the valve body, the channel so formed being an outlet from the receiving chamber.

60 3. In a mixing faucet, a valve body surrounding a mixing chamber and a receiving chamber, the receiving chamber having

two outlets, a passage arranged in the valve body in line with one of the outlets, a swinging discharge nozzle surrounding the receiving chamber, having passages arranged to register alternately with the respective openings in the receiving chamber, one of these passages being arranged to connect with the passage in the valve body when it registers with its respective opening in the receiving chamber.

70

75

4. In a mixing faucet, a mixing chamber, openings into the chamber from two sources of supply and a rotary valve in the chamber operating to control the relative flow from the openings, an outlet from the mixing chamber closed by a valve disc, which is located outside the chamber, a valve stem operating to lift the valve disc by a motion along its axis and operating to change the relative flow from the supply openings by 80 a separate rotary motion.

5. In a mixing faucet, a mixing chamber and a receiving chamber, a valve disc arranged in the receiving chamber operating to close the opening between the two chambers being a valve stem centrally located and extending through the valve disc into both chambers and a spring located in the receiving chamber operating to hold the disc 90 in its closed position.

95

6. In a mixing faucet, a mixing chamber and a receiving chamber, the receiving chamber having a cylindrical wall, a swinging discharge nozzle arranged to turn on the outside of the cylindrical wall and an outlet 100 in the wall to allow the water to pass into the discharge nozzle, a valve opening between the mixing chamber and the receiving chamber and a valve disc for the opening which operates to open and close the faucet.

105

7. In a mixing faucet, a centrally located valve having a valve disc, operated by a valve stem, means for imparting an axial motion or a separate rotary motion to the valve stem, two sources of water supply and a rotary valve arranged to control the relative flow from the two sources, the valve stem being extended through the valve disc for the purpose of operating the rotary valve.

110

8. In a mixing faucet, a mixing chamber having inlets from two sources of water supply, a rotary valve located in the mixing chamber, operating to open and close the inlets, a valve disc on the outlet of the mixing chamber, the disc being operated by a valve stem, the valve stem being connected to a cam on a valve lever, the cam being designed to hold the valve disc open when released in its open position.

115

9. In a mixing faucet, an operating lever connected to a rotary valve which is arranged to allow water to enter from either or both of two sources and to change the relative proportions of same by swinging 120

125

120

130

about a vertical axis, and a swinging discharge nozzle arranged to deliver water at either of two outlets by swinging the nozzle about the same vertical axis.

- 5 10. In a mixing faucet, a swinging discharge nozzle and a stationary discharge outlet, the swinging nozzle operating to divert the discharge from the stationary outlet to the swinging nozzle or the reverse when
10 the nozzle is rotated about a vertical axis and a valve operating to open and close the faucet independently of the movement of the swinging discharge nozzle.
